SCOURING PAD HOLDER

Orval G. Elliott, Rte. 8, Box 340, Dallas, Tex.

Filed June 17, 1960, Ser. No. 61,004

Term of patent 7 years

(Cl. D9—2)

The portions shown in broken lines in Figure 2 are for illustrative purposes only.

I claim:

The ornamental design for a scouring pad holder, as shown and described.
